UNITED STATES PATENT OFFICE.

ABE J. SHICKMAN, WALTER A. THUM, AND WILLIAM L. DEMPSEY, OF ST. LOUIS, MISSOURI; SAID THUM AND SAID DEMPSEY ASSIGNEES TO THE SAID SHICKMAN.

AUTOMATIC PRINTING PRESS.

Application filed October 30, 1924. Serial No. 746,764.

Our invention relates to automatic printing presses, and specifically to that class of automatic printing presses used to duplicate a typewritten letter.

5 The principal object of our invention is to provide a printing press that not only automatically feeds the blank paper into the machine, prints it and discharges it, but, also, automatically prints a different name 10 and address on each individual sheet that passes through it.

Another object of our invention is to produce an automatic printing machine, as indicated, that has relatively large capacity; 15 that is to say will print and address from 1000 to 1500 letters per hour.

Another object of our invention is the production of an automatic printing press consisting of a minimum of parts and of 20 relatively light weight, that will occupy a minimum of space and can be manufactured at a relatively small cost.

Other objects and advantages of our improved automatic printing press will be 25 obvious from the description and claims hereinbelow set forth.

Referring to the drawings made a part of this specification:

Fig. 1 is a side elevation of the main operating mechanism.

Fig. 2 is a plan view of some of the more important mechanism.

Fig. 3 and Fig. 4 taken together show a vertical cross-section.

35 Fig. 5 is a perspective of a portion of the reciprocating type bed, the addressing plate and, also, a roller guideway.

Fig. 6 is a perspective of an addressing plate.

40 Fig. 7 is a side elevation of a portion of the feeding mechanism, showing the paper in position to be fed to the printing roll.

Fig. 8 is a longitudinal view, partly in section, showing the mechanism for shifting 45 and reversing the inking ribbon.

The applicants are aware that automatic printing presses per se are not new. However, those now on the market are of relatively very large size and weight and are adapted only to doing commercial work on a rather large scale and consequently are 50 too expensive for economical use by individuals, firms and small corporations.

These machines are, also, intended to print only duplications from type already set up 55 and placed in the machine; hence, they are not adapted to be used for printing a facsimile of a typewritten letter on which each sheet has a different name and address.

To overcome these objections and to provide a machine that not only automatically prints a different name and address on each individual sheet printed, but can be sold at a price sufficiently low to meet the demand 60 of individuals and small firms, or in other words to meet a specialized requirement, the applicants have produced a machine capable of doing the same class and character of work done by the larger and more expensive machines now on the market, and also has 65 the additional feature of being able to print a different name and address on each individual sheet. These results are accomplished by the means and mechanisms hereinbelow described.

70 A suitable frame 1, preferably made of cast iron, is provided in which the entire mechanism functions, so that the completed machine consists of a single portable unit.

Power from an electric motor 2, or other 75 convenient source, is transmitted to the various mechanisms as later described.

The blank sheets to be printed are placed upon a platform 3, shown in Fig. 7, which is caused to move up by means of the tension 80 of a double-coil spring 4, in such a manner that the top sheet of the paper in the pile 5 presses lightly at all times against a guideway 6, so positioned that it guides the paper to the booster arms, later described.

85 In order to adjust the tension of the spring to paper of various weights, an adjusting nut 7 is provided and threaded on to a standard 8 by means of which the tension of the spring 4 is increased or decreased so that the top sheet of the pile rests lightly at all times against the guideway 6.

90 Crank arms 9 rotate clock-wise and transmit reciprocating motion to the connecting rods 10, pivotally connected to the crank arms 9. The opposite end of the connecting rod 10 is pivotally connected with a shoe 11, having a sole of rubber 12, or other tractive material, which during their forward reciprocation contact with the upper 95 surface of the paper with sufficient tension

to cause the paper to move forward with it. At the end of its reciprocatory movement studs 13 positioned in the connecting rods 10 at right angles to its longitudinal axes 5 passes between the flexible guideways 14 and on its return reciprocatory motion it rides on the top side of the guideways 14, thus preventing contact with the paper. At the end of the backward reciprocation, the studs 10 13 pass off the guideways at 15 and again contact with the next sheet of paper, and the cycle is thus continuously repeated.

This mechanism has brought the edge of the paper to a point adjacent the holding fingers 16, which at this instant are open. A plurality of booster arms 17 are rigidly attached to an oscillating shaft 18, provided with a torsion spring 19 which is held in tension during approximately two revolutions 20 of the printing roll, later on described, until they reach a point where the fingers 16 are open, when by means of the cam 20, cam arm 20^a and the cam roll 21, the tension upon the spring 19 is released causing a quick forward movement of the booster arms 17 which at this time are in contact with the sheet of paper to force the paper home against the stops 22 on the fingers 16, thereby ensuring the proper registering of the paper with the type form, later on described.

The fingers 16 are rigidly connected to a horizontal shaft 23. By means of a torsion spring 24, the fingers 16 are normally held in a closed position. On one end of the shaft 23 is rigidly attached a rocker arm 25, having in its end a roller 26, which follows the contour of cams 27 and 27^a alternately.

The cams 27 and 27^a are rigidly attached to a sleeve 28. The design of the cams is such that the fingers 16 are caused to open at the proper instant to receive the sheet to be printed and, also, opened at the proper instant to discharge the sheet when printed. The cams 27 and 27^a are shifted backward 45 and forward by means of a collar 29, reciprocably mounted upon a horizontal shaft 30, and a shifting fork 31. The shifting fork 31 is pivotally connected to the frame at 32, shown in Fig. 2, and is caused to oscillate 50 by means of a cam 33 rigidly attached to the shaft 34.

The purpose of shifting the cams 27 and 27^a is to provide for the opening of the fingers 16 upon one revolution for receiving the sheet to be printed, and opening them again on the next revolution at the proper instant to discharge the printed sheet.

When the paper is properly fed into the printing roll 35, the roller continues to rotate contra-clockwise. During this period of rotation the reciprocating bed plate 36, which carries the type form, has reached the limit of its stroke. At the same time, during a period of rest later on described, an addressing plate has been fed into the form

and the one already in the form has been discharged by a mechanism later described.

During the same period of rest, the bed plate 36 has been raised vertically by a mechanism later described and begins its return 70 reciprocatory movement in harmonic step with the rotation of the printing roll 35, which presses upon the type with sufficient force to ensure a proper impression.

The type is continuously inked by means 75 of a ribbon 37, wound on two spools 38 and 38^a, in one direction, and moving in one direction at graduated stages until the ribbon is unwound from one roll and wound upon the other. This operation is effected by 80 means of the mechanism shown in Fig. 8. On the end of each of the ribbon rolls 38 and 38^a are rigidly attached ratchet wheels 39 and 39^a, held against rotation by suitable braking mechanisms. An oscillating ratchet 85 bar 40 is pivotally attached to the immovable bed plate at 41. Upon each end of the bar 40, dogs 42 and 42^a are provided pointing in opposite directions.

It is evident that as the reciprocating bed 90 plate 36 moves in a direction opposite the point on the dogs 42 and 42^a, the one in contact with the ratchet wheel will cause the ribbon rolls to rotate in the direction of the 95 point of the ratchet dogs.

The oscillating ratchet bar 40 is held in tension by means of a coil spring 43. A flexible ratchet dog 44 is rigidly attached to the movable bed plate 36 and engages a ratchet wheel 45, rotatably attached to the 100 immovable bed plate 47. It is apparent that as the movable bed plate 36 reciprocates, the dog 44 will engage the teeth of the ratchet wheel 45 and cause it to rotate one tooth with each reciprocation.

The pinion wheel 48 is rigidly attached to and rotates with the ratchet wheel 45 and meshes with the gear 49, causing it to rotate with a greatly reduced velocity.

Integral with the gear 49 is a cam 50, so 110 designed as to provide a period of rest for one-half a revolution, during which time either one of the ratchet dogs 42 and 42^a is in contact with one of the ratchet wheels and, also, so designed that in the next half 115 revolution it provides a period of rest when the alternate end of the ratchet bar 40 is lifted so as to contact with the opposite ratchet wheel. Thus it will be understood that the ribbon moves in successive stages 120 a definite distance after each impression has been made and continues to move in one direction until near its end, when by the movement of the cam 50 the direction is reversed as above explained.

The movable bed plate 36 is caused to reciprocate by racks 51 and 51^a and gears 52 and 52^a, shown in Fig. 3. Gears 52 and 52^a are rigidly attached to the shaft 53, the outer end of which is rigidly affixed to a bevel 130

cog wheel 54, which alternately meshes with bevel gears 55 and 55^a, which in turn are rigidly affixed to a vertical driving shaft 56 which has a continuous rotary motion in one direction.

It is evident that as long as the bevel gear 54 meshes with the bevel gear 55^a, the rotation will be in one direction and the movable bed plate 36 will consequently move in one direction. It is, also apparent that when gear 54 is in mesh with gear 55, it will rotate in the opposite direction and will cause the bed plate 36 to operate in the opposite direction.

It will be noted that a number of cogs are deleted in the bevel gears 55 and 55^a, at 57, hence when the shaft 56 rotates to a point where the cogs are deleted at 57, the shaft will cease to revolve until the shaft 56 reaches the point to cause new cog contact between the bevel gears 54 and 55. This period of rest is so timed that it occurs at the end of each reciprocatory movement of the bed plate 36. This period of rest is further lengthened by means of the mechanism shown in Fig. 1.

The bed plate 36 is provided with four legs, or standards, 58 which rest on cams 59 and 59^a. Integral with the cams 59 and 59^a are rack wheels 60 and 60^a. A reciprocable bar 61 is provided at each end of which are racks 62 and 62^a that mesh with the pinions 60 and 60^a. The rack bar 61 is caused to reciprocate by means of the cam 63 rigidly mounted upon the shaft 64, which rotates in timed relation with the other mechanism of the machine so as to cause the point 63^a of the cam 63 to contact with the rollers 65 and 65^a.

It is evident that when the point 63^a contacts with the roller 65, it will cause the rack bar 61 to reciprocate in one direction, transmitting rotary motion to pinions 60 and 60^a, thereby rotating cams 59 and 59^a to a point that will raise or lower the standards 58 at each end of the reciprocating bed plate 36.

It will be noted that the rotatable shaft 53 is hung in bearing brackets 66 and 66^a, integral or attached to the stationary bed plate 47, so that when the bed plate is raised and lowered, it will cause the shaft 53 to be raised and lowered with it so that the bevel gear 54 first meshes with gear 55 and alternately meshes with gear 55^a, the cams 59 and 59^a being so designed as to cause a slight moment of rest thereby increasing the period of the rest of the reciprocable bed plate 36, at each end of its stroke.

It will be understood that cams 59 and 59^a are duplicated on the opposite side of the machine, the two cams designated as 59 being attached to shaft 67 and the cams designated as 59^a being rigidly attached to shaft 67^a. In this manner all the points of the surface of the bed plate 47 remain at all times

in the same plane relatively to the printing roll, thereby ensuring the uniformity of the pressure of the roll on the type.

When the printing of the sheet has been completed, the printing roll continues to revolve carrying the printed sheet to a point designated as A. Just prior to the time that the fingers on the printing roll have revolved to a point designated as A, a plurality of discharge fingers 68, rigidly attached to a horizontal shaft 69, are caused to come in close juxtaposition with the roll by means of a crank arm 70 pivotally attached to a rocker arm 71, which in turn is caused to oscillate about a stud 72 by means of the rotation of the cam 73, against which one end of the rocker arm 71 continually rides by means of the tension of the torsion spring 74.

In order that the proper pressure may be exerted on the type by the printing roll when paper of various thickness is used, a mechanism is provided for raising and lowering the roll, consisting of adjustable bearings 75 which may be raised or lowered by means of an adjustment bolt 76.

In order to mitigate the shock which would be transmitted to the machine by means of the reciprocation of the reciprocating bed plate 36, carrying the type forms, conventional pneumatic bumpers 77 are provided which consist of a piston 78 and buffer heads 79. It is evident that as the reciprocating bed plate strikes the head 79 it will cause the piston 78 to move inwardly compressing the air and thus cushioning the blow that otherwise would jar the machine when running at high speeds.

The upper surface of the reciprocating member 36 is planed to a perfect surface so the type locked in the usual manner in a conventional chassis may be adjustably placed and locked by means of conventional quoins and printer's furniture.

It is evident that should the printing roll continuously rotate and the reciprocating member 36 be caused to rest at each end of its stroke, the synchronism of the printing roll with the reciprocating plate would be destroyed. Therefore, in order to maintain the proper harmonic motion between these two elements, the printing roll is driven by means of bevel gears 80 and 81 being rigidly attached to shaft 30 to which the printing roll is, also, rigidly attached, and bevel gear 80 being rigidly attached to the main driving shaft 56. It will be noted that a number of cogs are deleted from bevel gear 80 at 82, for the purpose of causing the printing roll to rest during the same interval of time that the reciprocating member 36 rests.

In order that a new name and address may be printed on each sheet, a conventional addressing plate 83 is provided, on which the name and address has been previously embossed.

The plate 83 is made of sheet metal having its longitudinal marginal edges 84 formed in the shape of a right angle and adapted to engage slots 85 of the same contour and 5 slightly larger in the movable bed plate 36, and located near the inner end of the said bed plate at a point that will cause the address to be printed at a suitable distance from the body of the letter, the type for which is 10 shown at 86.

The plate 83 is cut out at 87 and adapted to engage a spring 88, which simply holds the plate from longitudinal movement when inserted.

15 When one impression has been taken from the plate 83, the plate is caused to move longitudinally forward by the pressure of the next succeeding plate and is discharged through the opening 89 into any suitable 20 receptacle.

The mechanism for inserting and discharging plates consists of a hopper 90 of suitable shape and dimensions carrying a number of plates placed flat-wise one above 25 the other, the lower end of which is positioned at a point where it will be in perfect alignment with the slots 85 when the bed plate 36 comes to rest.

A coil compression spring 91 is enclosed in 30 the tubular housing 92, one end of the coil spring 91 being held by the closed end of the tube 93 and the other end held against the head 94 of a reciprocable plunger rod 95. Attached to the outer end of the plunger 35 rod 95 is a dog 96, normally held by a spring in a position to adapt it to contact with the outer end of the lowest plate in the hopper, so that when the reciprocating plunger rod 95 moves inwardly, it forces the plate forward and when the reciprocating plunger rod 95 moves in the opposite direction by means of the spring 97, the dog 96 yielding 40 passes beneath the lower surface of the next succeeding plate, when the spring 97 again causes it to assume a more vertical 45 position and contacts with the outer end of the plate and forces it into the slots 85 in the reciprocable bed plate 36.

50 A vertically disposed roller 98 is rotatably attached to the under side of the outer end of the plunger rod 95 and is adapted to contact with a guideway 99. At the instant that the plate has been pushed into 55 position, the roller 98 is in front of the slot 100 in the guideway 99. On the reciprocatory motion of the bed plate 36, the roller 98 passes through the slot 100 along the side of the reciprocable bed plate 36 and beneath the end of the guideway 99 at 101 where 60 the guideway 99 is held in contact simply by its tension. As the bed plate 36 starts in the opposite direction the roller 98 rides on the outer surface of the guideway 99, which causes the plunger rod 95 to compress the spring 91. When the roller again 65

reaches the angle of the guideway at 102, the tension of the spring is released and drives the plunger arm 95 inwardly and being in contact with the plate 83 forces it into position and at the same time forces 70 the plate already in position forward where it drops by gravity through the opening 89 into a proper receptacle. This cycle of operation is continuously repeated.

75 Power for operating our improved automatic printing press is furnished by a motor or other suitable source and is transmitted by means of a worm 103 to the worm gear 104 and shaft 105, thence through a suitable clutch 106 to the bevel gear 107, rigidly attached to a suitable clutch sleeve, then it is communicated to the main driving shaft 56 by means of bevel gear 108. The power is then transmitted to all of the various working parts of the machine by suitable gears rotating at proper speeds and in the right direction to cause the machine to function entirely automatically.

Having fully described our invention and the method of its operation, what we claim 90 as new and useful and desire to secure by Letters Patent is:

1. An automatic printing press of the class described, comprising in combination, 95 an automatic paper sheet feeding medium provided with a spring and cam-actuated means for imparting accelerated motion to a sheet of paper at the instant it is being fed to a rotatable printing roll having gripping means for securely holding in a pre-determined adjusted position the sheets of paper thus accelerated, a reciprocating form-carrying frame adapted to rest for a period of time at each end of its inward and outward movement, automatic means for elevating said form-carrying frame during one of said periods of rest, means for rigidly holding said form-carrying frame in an elevated position during one full stroke, means for depressing said form-carrying, reciprocating frame during each alternate stroke of said frame. 100 105 110 115

2. An automatic printing press of the class described, comprising in combination, 115 a paper feeding mechanism, means for accelerating the sheets of paper being fed, a rotatable printing roll, means for holding sheets of paper fed to said roll, during the time said roll is in rolling contact with type rigidly locked in a reciprocating form- 120 carrying frame, an inking ribbon carried by said reciprocating form-carrying frame, disposed between said printing roll and said type, means for automatically shifting said inking ribbon axially along said form-carrying frame when said ribbon is not in contact with said printing roll and said type, guideways located in one end of said reciprocating form-carrying frame disposed at right angles to the major axis of 125 130

said frame, adapted to receive and hold address plates inserted therein, a hopper adapted to hold a plurality of address plates in close proximity to said guideways, 5 a spring-actuated plunger adapted to dislodge one of said address plates at a time from the bottom of said hopper, causing said dislodged plate to enter the said guideways and thereby discharge from said 10 guideways the address plate previously deposited in said guideways, means for limiting the longitudinal movement of said plunger, means for automatically compressing the spring actuating said plunger, and means for releasing the tension of said compression in timed relation with the movement of the said reciprocating form-carrying frame.

In witness whereof we have affixed our signatures this 27th day of October 1924.

ABE J. SHICKMAN.
WALTER A. THUM.
WM. L. DEMPSEY.
